[57] CLAIM

The ornamental design for an anteversion gauge for indicating degree of version in hip repair or replacement surgery, as shown and described.

DESCRIPTION

FIG. 1 is a front elevational view of an anteversion gauge for indicating degree of version in hip repair or replacement surgery showing my new design;

FIG. 2 is a right end elevational view thereof, the left end elevational view being substantially identical;

FIG. 3 is a rear elevational view thereof;

FIG. 4 is a bottom plan view thereof; and

FIG. 5 is a top plan view thereof.
